UNITED STATES PATENT OFFICE.

CARL WEILERT, OF CHICAGO, ILLINOIS.

DESIGN FOR DRAPERY.

46,613.

Specification for Design.

Patented Oct. 27, 1914.

Application filed July 9, 1914. Serial No. 850,019. Term of patent 7 years.

To all whom it may concern:

Be it known that I, CARL WEILERT, a citizen of the United States, residing at Chicago, in the county of Cook and State of Illinois, have invented a new, original, and ornamental Design for Draperies, of which the following is a specification, reference being had to the accompanying drawing, forming part thereof.

In the drawing, Figure 1 is a front vertical elevation of my ornamental design for a drapery, and Fig. 2 is a vertical end view of the same.

The design comprises a plurality of vertically elongated bands made of woven fabric that are hung pendently from a drapery rod secured in the door frame and are spaced apart. Interposed between these strips so that they are visible from either side of the drapery are garlands that are hung from

the same rod that supports the fabric strips, while at the upper portion of the drapery are other garlands hung in festoons and looped up at their ends. In this manner the garlands hanging in the open spaces between the strips of woven fabric may be readily observed from either side of the drapery and the foliage of said garlands will at various points lap over either face of said strips giving the impression to the eye that natural flowers and foliage are hung in the door opening.

I claim.

The ornamental design for a drapery as shown and described.

CARL WEILERT.
